Assor to
The Lowell Manufacturing Company.
Letters Patent No. 1771, dated June 16, 1863.

The schedule referred to in these Letters Patent and making part of the same will

Is all, whom it may concern:

But know, that I, Elmira J. May, of Lowell, in the County of Middlesex and State of Massachusetts, have originated and designed a new Pattern for Carpets or other fabrics, of which the following is a full, clear and exact description, reference being had to the accompanying drawings, making part of this specification.

1. is a large set figure composed of a star in the centre, two bands interwoven with each other, a wavy chain and four rows of leaves. 2. is a long set figure resting on the ground 1. 3. which is enclosed by a scroll frame, to which is attached sprigs of leaves.

3. and 4. at the sides when matched form a veined figure resting on a ground enclosed by the frame 5. 5. connecting the frame 5. 5. with figure 1. are the bands 6. 6. continuations of which extend under the leaves attached to the scroll frame before mentioned. The remaining parts of the design are either sections or repetitions of figures before specified.

The colors employed for the different portions of the design may be varied to suit the taste and mode of the manufacturer.

Claims.

What I claim as my invention and desire to secure by letters patent, is the design or pattern for Carpets or other fabrics, herein set forth.
